BOBBIN STRIPPER

Leonard Kleeble, Jr., Fall River, Mass., assignor,
by mesne assignments, to The Terrell Machine
Company, Charlotte, N. C., a corporation of
North Carolina

Application March 16, 1936, Serial No. 69,073

18 Claims. (Cl. 28—19)

This invention relates to bobbin strippers, particularly of the type employed to strip silk or rayon loom bobbins which must be stripped without marring or roughening of their smooth surfaces, such as would result in catching of the 5 silky yarn during weaving.

The hand stripping operations which, because of this limitation on mechanical stripping, have commonly obtained heretofore, have been slow 10 and expensive in labor costs, resulting in the suggestion that the bobbins be stripped automatically by conveying the bobbins past a rough-surfaced stripper roll against which the yarn ends are blown pneumatically, and employing, as 15 conveying mechanism, a moving belt carrying vertical spindles received within the axial bores of the bobbins. Although the pneumatic and stripper roll elements are effective for removing the yarn, the conveying mechanism heretofore proposed has its limitations in that it involves a 20 slow manual operation of placing the bobbins over the moving spindles. Furthermore, the natural downward hang of the end of the yarn to be removed cannot be taken advantage of in 25 removing the yarn in such apparatus as the conveying mechanism beneath the bobbins not only renders downwardly hanging yarn inaccessible, but it also requires the conveying of the bobbins in inverted position with their heads 30 lowermost, thereby necessitating the raising of the loose ends of the yarn into engagement with a stripper roll above the bobbins.

It is the object of the present invention to provide a machine of this character which is effective for the purpose and sufficiently rapid to supersede the present manual operations, and to that end I provide mechanism which utilizes the protrusion of the bobbin heads or the rings on the heads to provide support for the pendent 35 bobbins, in combination with feeding elements which engage the bobbins only at their heads.

In practice I have found that bobbins can be quickly and easily inserted in such a machine and rapidly conveyed thereby. The weight of the 40 silky yarn hanging over the tapering shank and tip of the bobbin, as aided, if desired, by jets of air, either effects the complete removal of the 45 yarn or conveys it to stripping mechanism, such as a brush-surfaced rotating cylinder, for its 50 complete removal.

These and further objects and advantages of my invention will appear from a more detailed description thereof taken in connection with the 55 accompanying drawings, in which:—

Fig. 1 is a side elevation view of the machine somewhat shortened in length;

Fig. 2 is a plan view of the machine, similarly shortened;

Fig. 2a is a detail perspective view of the belt 5 pressure strips;

Fig. 3 is an elevation view of the end of the machine as seen from the right in Figs. 1 and 2;

Fig. 4 is an enlarged vertical section taken on the line 4—4 of Fig. 2;

Fig. 5 is a vertical section taken on the line 5—5 of Fig. 1;

Fig. 6 is a perspective view of the right hand end of the machine as viewed in Figs. 1 and 2, 10 showing details of the bobbin track and belts;

Fig. 7 is a detail plan view as from the line 7—7 of Fig. 1;

Fig. 8 is a vertical section on the line 8—8 of Fig. 2;

Fig. 9 is an enlarged elevation view, partly in 20 section, of the end of the machine seen in Fig. 3 showing the clipper and the elements for guiding depending strands of yarn thereto;

Fig. 10 is an elevation view, partly in section, 25 as seen from the line 10—10 of Fig. 9;

Fig. 11 is a plan view of the clipper;

Fig. 12 is a plan view of a portion of the belts and rails of a modified construction;

Fig. 13 is a vertical section on the line 13—13 30 of Fig. 12; and

Fig. 14 is a detail perspective view of the modified form of track member.

To describe first the mechanism for feeding the bobbins during the stripping operation, the bobbins to be stripped, which may be of the form indicated at 1 in Fig. 5, are manually inserted in the mouth 2 (Fig. 2) of an inclined chute, comprising parallel spaced tracks 5 and 6 which incline downwardly from the inlet mouth and then turn horizontally (Fig. 4) to continue to the 40 outlet mouth 10 at the left hand end of the machine. As indicated, in Figs. 8 and 5, the tracks 5 and 6 are spaced apart the predetermined distance required to support the bobbins 1 by the usual rings 7 encircling the bobbin head 8, and 45 are spaced slightly from the side surface of the bobbin head.

The horizontal portions of the spaced tracks 5 and 6 are supported on a pair of angle iron frame members 11 and 12, the shape of which is best 50 indicated in Fig. 6 and which are mounted in any suitable manner on the legs 15 of the frame. For adjustably securing the spaced tracks 5 and 6 on the horizontal flanges of the frame members 11 and 12, the frame members are provided with a 55

plurality of brackets 20 (Fig. 2) spaced lengthwise of the frame members, each of which brackets is secured to the upper surface of its frame member by a bolt 21 (Fig. 8) passing through the bracket and into the frame member. The bent up end of each bracket is drilled to receive a bolt 25. The rails 5 and 6 are provided at intervals corresponding to the spacing of the brackets 20 with lugs 26 welded to the outer edges of the rails 5 and 6, which lugs have screw threaded apertures to receive the bolts 25. By rotation of the bolts 25 the tracks 5 and 6 may be adjusted toward and away from each other for accurate parallelism of the tracks at the desired distance apart. To secure the bolts 25 against turning after the desired adjusted position has been obtained, I provide the bolts with lock nuts 27 and for further securing the tracks in their adjusted position I secure the tracks at intervals with bolts 30 passing through elongated slots in the tracks and into the frame members 11 and 12.

The inclined portions of the tracks 5 and 6, indicated on the right in Figs. 1 and 2, are similarly supported, the tracks being adjustably mounted on frame members 31 and 32 (Figs. 2 and 3) extending upwardly to the inlet mouth at the inclination required for the desired gravity feed of bobbins to the horizontal portions of the tracks.

30 After the bobbins reach the bottom of the inclined chute they are conveyed along the horizontal tracks through the machine by means of a pair of belts 40 and 41 (Fig. 2) which, as indicated in Figs. 5 and 6, have adjacent parallel courses running immediately above the tracks. These adjacent inner belt courses move toward the outlet mouth at the same speed and by their pressure against the rings on the bobbin heads push the bobbins along the tracks 5 and 6. The belt 40 (Fig. 2) passes over horizontal pulleys 42 and 43 mounted on vertical shafts 46 and 47, both turning clockwise, and the pulley 43 is power-driven, as will appear. The belt 41 passes over horizontal pulleys 44 and 45 mounted on vertical shafts 48 and 49, both turning counter-clockwise, and the pulley 45 is power-driven.

The inner, bobbin-engaging courses of the belts 40 and 41 are relatively urged toward each other to press yieldingly against the rings on the bobbin heads. For that purpose the inner course of the belt 40 is backed up by an elongated angle iron 50, (Figs. 2 and 2a), which is mounted on top of the track 5 and secured thereto by bolts 51 (see also Fig. 5) passing through the horizontal web 55 of the iron 50, and into the track 5. Adjustment of the angle iron 50 to insure proper position of the inner course of belt 40 may be obtained by providing elongated slots in the angle iron 50 through which the bolts 51 pass and the horizontal web may be broken away at intervals, as indicated at 55 in Fig. 2a, to accommodate the aforesaid lugs 26 and bolts securing the track 5 to frame member 11.

60 The inner course of belt 41 is yieldingly pressed against the bobbin head rings by a similar angle iron attachment but, in this case, comprising a plurality of separate angle iron sections 60, as indicated in Figs. 2 and 2a. Each of these angle irons extending along the belt 41 is disposed on the track 6 (Fig. 6) and has elongated slots 61 receiving bolts 62 passing through the slots and into the track 6 (Fig. 5). In the case of the angle irons 60, however, the bolts 62 are not clamped tightly on the angle irons, but when 75 screwed home, permit freedom of sliding move-

ment of the angle iron 60 on the track 6 toward and away from the bobbins to cause the belt 41, in turn, to press against the bobbin head rings. To obtain a yielding pressure I provide a plurality of spring pressure members 70 spaced at intervals lengthwise of the tracks, as indicated in Fig. 2. The details of these members are shown in Fig. 6 and each comprises an angle iron 71 bolted to the frame member 12 as by the bolt 72 and having an upstanding member 73 through which 10 pass freely the bolts 75 (Fig. 2a) protruding from the belt-engaging flanges 78 of the angle irons 60. Interposed between the said flanges and the flanges 73 of the angle irons 71 are coiled springs 76 which yieldingly urge the angle irons 60 and 15 particularly the flanges 78 thereof, toward the bobbin heads. The inward movement of the angle irons 60 may be limited by nuts 80 received on the screw threaded ends of the bolts 75.

The purpose of providing a number of separate 20 spring pressed angle irons 60 lengthwise of the belt 41, rather than a single angle iron, is to insure that slight inequalities in the outer diameters of the rings on the individual bobbin heads do not interrupt the feed of the bobbins through 25 the machine. Thus, if one long angle iron were provided, the distance between the belts might be determined by the external diameter of the largest bobbin head passing through the machine.

At the inlet end of the machine, as indicated 30 at 210 in Fig. 1 and as shown in detail in Figs. 9-11 inclusive, I provide a cutter element for cutting off unusually long strands of yarn which may be hanging from the bobbins, in combination with guiding elements for directing the strands 35 of yarn to the cutter.

The cutter 210 is of a common type having co-operating toothed edges which reciprocate relative to each other as in the ordinary hair clipper. The particular construction of the cutter forms 40 no part of my invention and accordingly need not be described. The shaft which drives the cutter has a bevel gear 211 secured to its end, which meshes with the gear 212 on one end of a shaft 213 which carries fixed to its other end a bevel gear 214 meshing with a bevel gear 215 secured to the end of shaft 160 driven in a manner herein-after to be described.

The clipper 210 is supported by suitable brackets from the frame 15 of the machine, as indicated, to position the cutter a predetermined distance below the tracks of the inlet chute, depending upon the length of yarn to be severed, and intermediate the tracks, as indicated in Fig. 9. For the purpose of guiding the yarn to the cutter I provide guides such as a U-shaped wire strip 220 secured to the angle irons 31 and 32 of the chute 2 by screws, and a pair of flaring guide strips 225 secured to the angle irons 31 and 32 on each side of the tracks and of the U-shaped 60 guide 220 to form a mouth delivering depending strands of yarn into the U-shaped guide member 220 and thence to the cutter 210.

As the bobbins are moved longitudinally of the machine over the parallel tracks 5 and 6 by means 65 of the belts 40 and 41, the yarn remnants to be removed, which usually take the form and position indicated at 100 in Fig. 5, are acted on by three agencies to remove the yarn. First, the weight of the yarn itself is frequently sufficient 70 to commence the unwinding of the silky yarn when the bobbin is supported in pendent position with tip lowermost. Second, I may provide a plurality of compressed air jets disposed along the path of travel of the bobbins to direct streams 75

of compressed air against the yarn remnants to be removed. These jets may suitably comprise a plurality of orifices formed in compressed air pipes 105 which are secured, as by brackets 106 (Fig. 5) to the inner upright faces of the frame members 11 and 12 and the orifices in the air pipes 105 should be so positioned as to direct streams of air against the bobbins in the downwardly inclined directions indicated in Fig. 5. The pipes 105 communicate with a supply of compressed air in any suitable manner such as by the pipes 107 (Fig. 3).

The yarn ends which are thus carried downwardly by the combined effect of gravity and compressed air, may be engaged by a third agency in the form of a rotating cylinder 110 on the periphery of which is disposed a number of longitudinally extending brushes 111 (see also Fig. 3). Engagement of the yarn ends by these brushes causes the yarn to wind up on the surface of the cylinder and complete its removal from the bobbins.

It will be observed that after the yarn end of an individual bobbin has first been caught by a certain portion of the periphery of the cylinder 110, continued movement of the bobbin through the machine, as induced by the travelling belts, causes the bobbins to move out of vertical alignment with that portion of the cylinder which has engaged the depending yarn. To prevent canting of the bobbins as a result of this movement, I provide the guide strip 125 (Fig. 6) which is at least coextensive with the cylinder 110. The said guide strip 125 comprises merely a piece of metal which rests on the flat tops of the bobbin heads, as indicated in Fig. 5, and by its own weight maintains the bobbins in a substantially vertical position but with pressure insufficient to cause the lowermost ring 7 to jam against the tracks 5 and 6. The strip 125 may conveniently be secured to the frame of the machine over the course of the bobbins by being bent upwardly and back on itself at its opposite ends, as indicated at 126 and 127 in Fig. 1. To permit entrance of the bobbins beneath the strip 125, the entering bent end 126 is supported by the bracket 128 straddling the tracks, as indicated in Fig. 6, and secured to the frame members 11 and 12 by the bolts 130 and 129. The end 126 is secured by bolt 135 and nut 133 (Fig. 4) to the bracket to support the entering end of the strip 125 with a slight clearance above the bobbin heads. With the exception of this supported entering end, the guide strip rests by its own weight on the bobbin heads. Intermediate its ends, the strip 125 is maintained in aligned position over the tracks, as indicated in Fig. 5, by a spindle 140 protruding from the upper surface of the strip 125 and passing freely through an aperture in the bracket 141 secured to the frame members 11 and 12 in a manner similar to the bracket 128. The spindle 140 has an enlarged head 142 which prevents the strip 125 falling down between the belt courses when no bobbins are passing through, but does not relieve the bobbin heads of the weight of the strip 125.

Similarly, at its outlet end 127 the strip is positioned over the bobbins by a bracket 145 (Fig. 1) receiving freely a spindle projecting from the top of the end 127 of the strip, thereby permitting the strip to rest on the bobbin heads by its own weight.

As stated above, the pulleys 43 and 45 are power driven to drive the belts 40 and 41. To insure equal speed of the belts, the pulleys have the same diameter and the pulleys 43 and 45 are geared to

gether by the similar intermeshing gears 150 and 151 which, as indicated in Fig. 3, are disposed at the lower extremities of the vertical shafts 47 and 49 to the upper ends of which the pulleys 43 and 45 are secured. To drive the shaft 49 from an electric motor 153 the gear 151 on shaft 49 meshes with idler 167 engaging gear 165 fixed on shaft 164 which (Fig. 1) has secured to it the large bevel gear 163 meshing with bevel pinion 162 on horizontal shaft 160. The shaft 160 is rotated by a large pulley 159 over which runs a belt 158 extending around a smaller pulley 157 fixed to shaft 156, which shaft is driven by the belt 154 extending around pulley 155 on shaft 156 and a pulley on the shaft of the motor 153.

The cylinder 110 is mounted on the aforesaid shaft 160 which is power-driven from the motor 153 by the belts above described to rotate the cylinder.

As indicated in Fig. 7, my apparatus includes mechanism for counting the stripped bobbins as they are expelled from the mouth 10 of the track and fall into a suitable receptacle. This device consists of a small cylindrical roller 170 rotatably mounted in the forked arm 171 to project over the track 5 and slightly into the path of travel of the bobbins for engagement by the rings 7 on the bobbin heads (see also Fig. 8). The forked arm 171 is secured as by rivets 172 to a strip of spring steel 173 near one end thereof, the other end of the strip being secured as by rivets 174 to a bracket 175, suitably secured to the track 6 to dispose the strip 173 substantially parallel to the path of travel of the bobbins. At its end adjacent the roller 170 the strip 173 carries riveted to it a shorter length of spring steel 180 having a nub 181 engaging a plunger 182 extending into the box 186 of an electric contact device of any suitable nature. The plunger 182 may be mounted on one end of a short piece of electrically conducting spring steel 183, the other end of which is secured to the binding post 185 from which the lead 204 extends. The spring strip 183 has at its extremity opposite the binding post 185, an electric contact 187 which co-operates with a contact 188 on the extremity of a companion electrically conducting spring strip 189 secured at the binding post 190. The wire 191 from the binding post 190 leads to a suitable source of current 200 which is connected in series with any suitable electric counting device 201 well known in the art, through which the circuit is completed by the aforesaid lead 204. It is apparent from this construction that depression of the spring strip 173 upon movement of the roller 170 by a passing bobbin will close contact between the members 187 and 188 to actuate the counter 201. By this mechanism for closing electric contact upon the passing of a bobbin, I insure not only that the progress of the bobbins through the machine is not impeded by the roller 170, but I also insure actuation of the counter, regardless of slight variations in the outer diameter of the rings on different bobbins.

In Figs. 12 to 14 inclusive I have shown a modified embodiment of my invention which is perhaps best adapted for use where the heads or rings of the bobbins vary considerably in size. In this construction the belts 340 and 341 are driven from pulleys 342 and 344 just as in the embodiment first described and the track 305, corresponding to the track 5 of the first embodiment may be secured to the frame member 311 in the same manner. This track supports the same type of strip 350 for backing up the belt 351

340. In this embodiment, however, the track 306 differs from the track 6 in that it is formed of a large number of sections, each shaped as indicated in Fig. 14 and having a flange portion acting as the track 306, a web 378 integral with the track 306 for backing up the belt, and a turned over flange 379 for guiding the upper edge of the belt. Each of these track sections is provided with a pair of feet 380 which slidably rests 10 on the angle iron frame member 312.

To press yieldingly these track sections toward the bobbins, the vertical web 378 is provided with a cylindrical member 390 received in a tubular socket 391 of a bracket 394 secured to the frame 15 member 312 by a bolt 392. A spring 393 encircling the socket 391 of the bracket and extending between the web 378 of the track member and the bracket 394 yieldingly urges the track section and belt toward the bobbins and this 20 movement may be limited by a stop screw 400, as indicated.

By so providing one of the tracks in sections, not only are the belts yieldingly pressed toward the bobbins at many places so that a substantial 25 variation in the width of the bobbin heads is ineffective to interrupt the feed, but the tracks themselves may vary in their spacing depending upon the varying protrusion of the bobbin rings.

By the provision of the flange lip 379 on the 30 top of the belt engaging web 378 I insure that the belt 341 does not ride up on the bobbin rings as might sometimes happen. Of course a similar flange may, if desired, be provided on the member 350 on the opposite side of the track.

35 I claim:

1. In a machine for stripping bobbins, the combination of a pair of tracks spaced apart to support, between them, bobbins in pendent position with their tips lowermost, at least one of said 40 tracks being in sections and having means yieldingly urging the track sections toward the opposite track, and bobbin engaging means movable longitudinally of the machine above the tracks for feeding bobbins so supported.

45 2. In a bobbin stripping machine, the combination of spaced tracks for supporting the bobbins in pendent position with their tips lowermost, movable band elements having oppositely disposed courses extending above and substantially parallel to the tracks to engage the sides of bobbin heads so supported, and means relatively urging the band courses toward each other to effect yielding pressure of the band courses 50 against the bobbin heads.

55 3. In a bobbin stripping machine, the combination of spaced parallel tracks for supporting the bobbins in pendent position with their tips lowermost, movable band elements having oppositely disposed courses extending above and parallel to the tracks to engage the sides of bobbin heads so supported, and means relatively urging the band courses toward each other for yielding pressure of the band courses against the bobbin heads, comprising a rail contiguous to one of 60 the band courses to restrain movement of that band course laterally away from the track, and means yieldingly urging the opposite band course toward the first band course.

4. In a machine for stripping bobbins, the combination of spaced tracks for supporting the bobbins in pendent and vertical position with their tips lowermost while the yarn is being removed therefrom by unwinding the yarn over the tips of the bobbins, a plurality of air jets disposed 70 along the tracks for directing streams of air 75

downwardly and against the bobbins so supported to blow yarn remnants, on said bobbins, downwardly beyond the tips thereof, and means traveling lengthwise of the tracks for feeding the bobbins along the tracks whereby to move the 5 bobbins through the air streams issuing from said jets.

5. In a machine for stripping bobbins, the combination of spaced tracks for supporting the bobbins in pendent and vertical position with their 10 tips lowermost while being moved one after another along such tracks, a plurality of air jets disposed along the tracks for directing streams of air downwardly and against the bobbins so supported to blow yarn remnants, on said bobbins, downwardly therefrom beyond the tips thereof, and a rotatable stripper roll disposed 15 lengthwise of the tracks and beneath the moving bobbins for catching the ends of yarn remnants gravitating and blown from the bobbins 20 and drawing off the remaining yarn from the bobbins.

6. In a machine for stripping bobbins, the combination of spaced tracks for supporting the bobbins in pendent and vertical position with 25 their tips lowermost while being moved one after another along such tracks, a plurality of air jets disposed along the tracks for directing streams of air downwardly and against the bobbins so supported to blow yarn remnants, on said bobbins, downwardly 30 beyond the tips thereof, a rotatable stripper roll disposed lengthwise of the tracks and beneath the moving bobbins for catching the ends of yarn remnants blown from the bobbins and drawing off the remaining yarn from 35 the bobbins, and means adapted to engage the tops of the bobbin heads during their movement along the tracks to prevent canting of the bobbins out of their vertical position on the tracks during the stripping. 40

7. In a machine for stripping bobbins, the combination of spaced tracks for supporting the bobbins in pendent position with their tips lowermost, a plurality of air jets disposed along the tracks for directing streams of air downwardly 45 and against the bobbins so supported to blow yarn remnants, on said bobbins, downwardly beyond the tips thereof, movable bands extending parallel to and above the tracks adjacent the bobbin heads, and means pressing the bands 50 against the sides of the bobbin heads whereby to feed the bobbins along the tracks and through the streams of air issuing from said jets.

8. In a machine for stripping bobbins, the combination of spaced tracks for supporting the bobbins in pendent position with their tips lowermost, a plurality of air jets disposed along the tracks, for directing streams of air downwardly and against the bobbins so supported to blow 55 yarn remnants, on said bobbins, downwardly beyond the tips thereof, a pair of bands extending parallel to and above said tracks, one band adjacent each track, means for moving both bands at substantially the same rate of speed and means yieldingly pressing the bands against opposite 60 sides of the bobbin heads to feed the bobbins along the tracks and through the air streams issuing from said jets.

9. In a machine for stripping bobbins, the combination of spaced tracks for supporting the bobbins in pendent position with their tips lowermost, a plurality of air jets disposed along the tracks for directing streams of air downwardly and against the bobbins so supported to blow 70 yarn remnants, on said bobbins, downwardly be- 75

yond the tips thereof, a pair of bands extending parallel to and above said tracks, one band adjacent each track, means for moving both bands at substantially the same rate of speed, and a plurality of pressure applying members disposed at intervals along at least one of said bands for pressing the bands against opposite sides of the bobbin heads at successive intervals along the bands to feed the bobbins along the tracks and through the air streams issuing from said jets.

10. In a machine for stripping bobbins, the combination of spaced tracks for supporting the bobbins in pendent position with their tips lowermost, a plurality of air jets disposed along the tracks for directing streams of air downwardly and against the bobbins so supported to blow yarn remnants, on said bobbins, downwardly beyond the tips thereof, a pair of bands extending parallel to and above said tracks, one band adjacent each track, means for moving both bands at substantially the same rate of speed, a plurality of pressure applying members disposed at intervals along at least one of said bands for pressing the bands against opposite sides of the bobbin heads at successive intervals along the bands to feed the bobbins along the tracks and through the air streams issuing from said jets, a rotatable stripper roll disposed beneath the moving bobbins for catching yarn remnants blown from the bobbins and removing them from the bobbins, means to restrain canting of the bobbins, on the tracks during the stripping, and a cutter, disposed at the inlet end of the machine, for trimming the yarn remnants before the bobbins are introduced to the air streams.

11. In a machine for stripping bobbins, the combination of a pair of tracks spaced apart to support between them bobbins in pendent position with their tips lowermost, at least one of said tracks having means yieldingly urging the tracks toward each other, and bobbin-engaging means movable longitudinally of the machine above the tracks for feeding bobbins so supported.

12. In a machine for stripping bobbins, in combination, spaced tracks supporting the bobbins in pendent relation by engagement with surfaces on the heads of the bobbins, means engaging the exterior surfaces of portions on the heads above the tracks and having movement lengthwise of the tracks to feed the bobbins along the tracks, and pneumatic means ejecting streams of air against the yarn remnants to be removed below the tracks.

13. In a bobbin stripping machine, the combination of spaced tracks supporting the bobbins in pendent relation with their tips downward, a driven endless band element having a course extending above and substantially parallel to the tracks to engage the heads of bobbins so supported, and means relatively urging the band element and bobbin heads together to effect driv-

ing engagement of the bobbin heads with the band element.

14. In a bobbin stripping machine, the combination of spaced tracks supporting the bobbins in pendent relation with their tips downward, a driven endless band element having a course extending above and substantially parallel to the tracks, and means causing the endless band element to propel the bobbins by pressing such element's surface against portions on the exterior of the heads of bobbins so supported.

15. Apparatus for stripping bobbins including in combination means supporting the bobbins in pendent and vertical relation through engagement with the outside surface of portions on the heads thereof, and defining a path, means drawing off axially of the bobbins, the yarn remaining thereon, and an endless traveling surface pressing against portions on the heads of the bobbins and by such engagement moving the bobbins along such path while the yarn is being unwound therefrom.

16. Apparatus for stripping bobbins, including an endless traveling surface engaging the outside surface of portions on the heads of bobbins and thereby moving the bobbins along a path while hanging by their heads while the remaining yarn on the bobbins is being unwound over the tips thereof, and mechanical means acting to prevent the bobbins from tilting out of vertical relation.

17. Apparatus for stripping bobbins having in combination spaced tracks supporting the bobbins in pendent, vertical, and laterally movable relation by engagement with surfaces in connection with portions on the heads thereof, pneumatic means blowing downward the yarn remnants on the bobbins, means removing the remaining yarn from the bobbins by unwinding it over the tips of the bobbins while pendent from the tracks, and means extending below and along the tracks on both sides of the pendent bobbins to confine the effect of the blast to the immediate vicinity of the barrels of the pendent bobbins.

18. Apparatus for stripping bobbins including in combination spaced tracks supporting the bobbins by their heads in pendent vertical relation for lateral sliding movement along the tracks under the push of the following bobbins, means preventing the heads of the bobbins thus pushed from tilting or rising from the tracks, and a roll acting to strip the bobbins by catching and unwinding the yarn remnants therefrom while thus supported by the tracks and prevented from tilting out of vertical relation and from rising, the axis or the periphery of the roll being in a plane parallel with the tracks and the roll extending along the tracks beneath the bobbins so that the point of engagement of the roll with the yarn from any one bobbin travels along the roll at substantially the same rate as the bobbin travels along the tracks.

LEONARD KLEEB, JR.
